[57] CLAIM

The ornamental design for a compartmented food serving tray, as shown.

DESCRIPTION

FIG. 1 is a top perspective view of a compartmented food serving tray showing my new design;
FIG. 2 is a top plan view thereof on an enlarged scale;
FIG. 3 is a side elevation viewed in the direction of arrow 3 shown in FIG. 1;
FIG. 4 is an end elevation taken in the direction of arrow 4 in FIG. 1;
FIG. 5 is a side elevation taken in the direction of arrow 5 in FIG. 1;
FIG. 6 is an end elevation taken in the direction of arrow 6 in FIG. 1; and
FIG. 7 is a section taken along line 7—7 of FIG. 2.

Fig. 2.
